(57) CLAIM

The ornamental design for a pair of push-up bra pads, as shown and described.

DESCRIPTION

FIG. 1 is a perspective front view taken from a top left side of a push-up bra pad;

FIG. 2 is a front elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a rear elevation view thereof;

FIG. 8 is a perspective front view taken from the top right side thereof; and,

FIG. 9 is a front view of two push-up bra pads, wherein the one on the right breast of the wearer is the push-up bra pad shown in FIGS. 1-8, and the one on the left breast of the wearer being a mirror image thereof.

The long-short-long broken lines in the drawings define the bounds of the claimed design and form no part thereof. The partial human figure shown in broken lines in FIG. 9 illustrates the environment in which the design is used and forms no part of the claimed design. The stippling shown in the drawings represents shading of the push-up bra pad.
